Primary Examiner — T. Chase Nelson*Assistant Examiner* — Jonathan J. Han(74) *Attorney, Agent, or Firm* — Honigman Miller Schwartz and Cohn LLP(57) **CLAIM**

The ornamental design for a firearm stock, as shown and described.

DESCRIPTION

FIG. 1 is a front/right side isometric view of an embodiment of the firearm stock of the present invention;

FIG. 2 is a front elevational view of the stock of FIG. 1;

FIG. 3 is a rear view of the stock of FIG. 1;

FIG. 4 is a right side elevational view of the stock of FIG. 1;

FIG. 5 is a left side elevational view of the stock of FIG. 1; FIG. 6 is a top plan view of the stock of FIG. 1; and,

FIG. 7 is a bottom view of the stock of FIG. 1.

The broken lines in the figures are used to illustrate unclaimed parts of the invention and form no part of the claimed design.

1 Claim, 4 Drawing Sheets(56)
